AUTOMATIC DIE

Robert R. Finn, Springfield, Vt., assignor to Jones & Lamson Machine Company, Springfield, Vt., a corporation of Vermont

Application December 22, 1941, Serial No. 423,876

15 Claims. (Cl. 10—95)

This invention relates to automatic screw threading dies and has for an object to provide a die which can be opened and closed automatically but when closed may be locked against premature opening as might otherwise be caused by rapid indexing of a lathe turret supporting the die.

A further object is to provide a die which, when operating on the work, is unlocked in condition to be released and opened when threading has progressed to the desired extent.

Still another object is to provide a construction wherein the die can progress with the work under light pressure so as to avoid stripping of work threads of very fine pitch.

Another object is to provide a die which may be locked closed when presented to the work but which by such presentation is automatically unlocked and conditioned for automatic opening when threading of the work has proceeded to a predetermined extent.

For a more complete understanding of this invention, reference may be had to the accompanying drawings in which

Figures 1, 2 and 3 are side, front and rear elevations, respectively, of a die embodying the invention, the die being closed and locked, Figure 2 being partly broken away and in section.

Figure 4 is a longitudinal section on line 4—4 of Figure 2, but with parts broken away or omitted.

Figure 5 is a view similar to a portion of Figure 4, but showing the die in cutting and unlocked condition.

Figure 6 is a cross sectional view on line 6—6 of Figure 4.

Figure 7 is a fragmentary longitudinal section on line 7—7 of Figure 6.

Figure 8 is a detail section on line 8—8 of Figure 7.

Figure 9 is a detail section on line 9—9 of Figure 4.

Figure 10 is a view similar to Figure 9, but showing the die in working and unlocked condition.

Figure 11 is a view similar to Figure 9, but showing the die released by contact of the release rod with a stop.

Figure 12 is a fragmentary perspective view of the die holder.

Figures 13 and 14 are perspective views of the die opening and closing ring and of the locking and opening and closing actuating cam ring, respectively.

Figure 15 is a section on line 15—15 of Figure 4.

Figures 16 and 17 are views similar to Figure 15, but showing the parts in cutting and released positions, respectively.

Figures 18, 19 and 20 are detail sections on the correspondingly numbered section lines of Figures 15, 16 and 17, respectively.

Figure 21 is a view partly in side elevation and partly in section showing the die in open position, the release having been effected by stopping the progress of the die holder when threading has progressed to the desired extent.

The die as shown comprises a sleeve 1 having a shank portion 2 and an enlarged diameter head 3. The shank portion 2 is supported for limited axial motion in a holder 4. The head portion 3 has an integral face plate 5, as shown in Figure 1, having dovetailed ways 6 therein for the reception of chaser carrying blocks 7 to which chasers, as 8, may be secured. Back of the face plate 5 and slidably axially on the head 3 is a die opening and closing member 10 shown detached in Figure 13. This member 10 has on its forward face outwardly inclined fingers 11 which project through openings 12 of the face plate 5 and engage in mating openings 13 in the chaser blocks 7. As the member 10 is moved forwardly from the position shown in Figure 21 to that shown in Figure 4, the chasers and blocks are moved substantially radially toward the axis of the die thus to close the die in condition for operating on the work as shown in Figure 2. By moving the member 10 rearwardly from the position shown in Figure 4 to the position shown in Figure 21, the chaser carrying blocks are moved outwardly thus opening the die.

The member 10 is pressed toward its open position as by means of springs 15 seated in recesses 16 and 17 of the face plate and ring 10, respectively, and the die is closed and held in closed position by means of a cam plate 20, shown detached in Figure 14. This cam plate 20 has inclined cam faces 21 adapted to engage cam faces 22 on lugs 23 on the back face of the member 10, the cam faces 21 of the member 20 at times being positioned between the cam lugs 23 in which position the die is maintained open by the springs 15. By rocking the member 20 from this angular position, however, the cam faces 21 may be moved in engagement with the cam faces 22, causing the member 10 to be wedged forwardly into closed die position. This member 20 is rockably mounted on the head 3 and is held up against the rear face of the mem-

ber 10 by means of a disk 25 backed up by a nut member 26 threaded onto the rear end portion of the head 3. Adjustment of this nut 26 determines the extent of inward motion of the chasers to closed position. Means are shown for retaining the nut 26 in adjusted position comprising a pointed screw 28 engaging between serrations 29 in the periphery of the nut 26, this screw being carried in a casing member 30 secured to the ring 25 and being adjustable in and out by means of a manually engageable head 31.

The ring 25 is held against turning by a pair of lugs 32 and 33 projecting through slots 34 therein, these lugs being integral with a flange portion 35 of the die holder 4. As is well known in the art, the shank portion of this die holder may be clamped in position in a suitable tool holder such as a turret of a turret lathe. While the lugs 32 and 33 extend into the plane of the ring member 20, there is sufficient clearance in this ring member to permit rocking motion of the ring member 20 between one angular position where the lugs 33 can pass between the cam faces 21, the die then being in open position, as shown in Figure 20, to a die closed position shown in Figure 19 and to a still further and locking position shown in Figure 18. This latter position will be more fully described later.

The holder 4 adjacent to the lug 33 is provided with a sleeve 36 which may be pressed into a hole therein as shown in Figure 4, this sleeve 36 having a notch 37 at one side at 31 (see Figures 9 and 12). Adjacent to the sleeve 36 a cone pointed screw 40 is threaded through the member 35 and a nut 41 is threaded on its opposite end to bear against the back face of the portion 35 by which the extent that the cone point projects from the forward face of the portion 35 may be adjusted and fixed. This cone point projects toward the back edge of a notch 42 in a radial extension or wing 43 of the member 20, (Figures 14 to 17), and adjacent to this notch 42, this member 43 is shown as provided with a flat headed plug 44. In the locked angular position of the member 20, this plug 44 is partly in alignment with the face 45 at one side of the notch 31 of the sleeve 36 as shown in Figure 9, so that in this angular and axial position of the member 20, the member 20 has a limited forward axial motion with respect to the sleeve 36 before it strikes the face 45 of the sleeve. When the member 20 is in the angular position corresponding to Figure 19 where the die is closed but not locked, this member 44 is out of alignment with the portion 45 of the sleeve and there is therefore a more extended range of relative axial motion between these parts, and this more extended relative axial motion is also possible when the die is in open position as in Figure 20.

The die head is normally held slightly forward axially with respect to the holder 4 as by means of spring-pressed plugs 48 (see Figure 4) in which position the cone point 40 is sufficiently retracted from the edge of the slot 42 so that the member 20 may be turned to locking position. As the die is pressed forward by pressure exerted on the holder 4 against the work, the die head retracts relative to the holder 4 into the position shown in Figure 5. This causes the cone point 40 to be pressed against the edge of the slot 42 and rocks the ring member 20 from the die-locked position of Figure 18 to the die-closed position of Figure 19, and permits an outward motion of the die head relative to the holder 4 beyond that per-

mitted when the ring 20 is in locking position, since the member 44 is then out of impinging relation to the face 45 of the limiting sleeve. If thereafter the holder 4 be held so that the die, while in engagement with the work continues to be threaded thereonto, the cam face 46 of the wing 43 strikes against an oppositely inclined face 50 of a rod 51 carried within the sleeve 36 and is crowded angularly into die-released position of Figure 20, whereupon the die is immediately opened by the action of the springs 45. This released axial position of the die head with respect to the holder 4 is shown in Figure 21.

The rod 51 has a limited axial motion in the sleeve 36, being prevented from becoming detached therefrom, as shown in Figure 4, by means of a pin 52 projecting across the bore of the sleeve 36 and engaging in a slot 53 of the rod 51. The rod 51 is normally pressed forward as far as permitted by the slot 53 and the pin 52, as by means of a spring 54 reacting between the forward end of the sleeve 36 and a collar 55 pinned to the rod 51. As soon as the die is opened and thus released from the work, it is drawn back with respect to its holder 4, this being accomplished by a light coil spring 60 (see Figures 4 and 21) seated in a socket 61 in a plug 62. This plug has an enlarged diameter portion 63 forming a pressed fit in the rear end of the holder 4 and having a flange 64 overlapping the rear end of this holder. This spring reacts against the base of the socket 61 and a collar 65 held in position by the head of a screw 66 threaded into the rear extremity of a headed rod 67, the head 68 of which may engage in a counterbored portion 69 within the head 3. This head 3 is open at its forward end as at 70 to permit the insertion of the rod 67. The rod 67 has a reduced diameter rear end forming a shoulder 71 which may abut the forward end of the plug 63, limiting the extent to which spring 60 may draw back the shank 2 to the position shown in Figure 4. This spring 60 is very light so that it will not exert sufficient retractive pressure on the die to cause stripping of the threads on the work when these threads are very fine, it being only sufficiently heavy to cause the return of the head to the position shown in Figure 4 when the die has been released from the work. This spring of itself would be insufficiently heavy to prevent centrifugal force exerted on the head during the indexing of the turret carrying the die causing forward motion thereof sufficient to open the die, but this is prevented when the ring 20 is in locking position by impingement of the member 44 against the shoulder 45 of the sleeve 36. When the die is in idle position, therefore, the ring 20 is turned to locking position, such motion acting first to close the die, by any suitable means as is well known in the art, so that the portion 43 engages the sleeve 36 as shown in Figure 18.

It will be noted that there is lost motion between the shank 2 and the plug 62 unaffected by the spring 60 between the positions of the head shown in Figures 4 and 5. The die is thus free to follow the lead of the threads on the work to a sufficient extent to allow for errors in accuracy of the feeding mechanism, its position being controlled only by the pressure of the spring-pressed plugs 48.

The die is then closed and locked and the various parts are in the position shown in Figures 1 to 9, 15 and 18. When the die is presented to the work by forward pressure exerted on the holder 4, the die head is pressed rear-

wardly into the position shown in Figure 5, retracting the spring pressed pins 48 and causing the cone point of the screw 40 engaging the back edge of the notch 42 of the wing 43 to rock the member 20 so that its member 44 is no longer in line with the shoulder 45.

The die is now closed but unlocked and when the threading has proceeded almost to the desired extent, the die may be opened by either of two methods. One of these methods consists in stopping the forward travel of the holder 4 with the die head as has been described. Another method of opening the die consists in stopping the forward movement of the rod 51 as by impingement upon a stationary stop 72 as shown in Figure 11. The forward movement of the die after this occurs causes the rod 51 to be retracted within the sleeve 36 against the pressure of the spring 54, causing the inclined face 50 thereof to impinge on the cam face 46 of the wing 43 and rock the member 20 to die open position.

In order to prevent access of dirt to the interior of the die, a circular shield member 75 surrounding and carried by the member 20 and bridging over into a reduced diameter portion 76 of the face plate portion 5 may be employed.

From the foregoing description of an embodiment of this invention, it should be evident to those skilled in the art that various changes and modifications might be made without departing from the spirit or scope of this invention.

I claim:

1. In a die comprising a head, a holder for said head with respect to which said head has a limited axial lost motion, chasers carried by said head and normally biased to open positions, means movably mounted on said head for closing said die and for holding said die closed, and means actuated by motion of said head axially toward one limit of said lost motion for moving said movable means to release said die to open, means supporting said movable means for motion from die open position beyond closing position to locking position, means coacting with said movable means when said movable means is in locking position to prevent axial motion of said head relative to said supporting means to die released position, and means carried by said holder and cooperating with said movable means to move said movable means out of locking position to die closed holding position by relative axial motion between said head and holder toward the other limit of said relative motion.

2. A die comprising a head, chasers supported by said head for motion between die open and die closed positions, a member movably carried by said head and having operative engagement with said chasers for closing or opening said die by motion of said member, means biasing said member to die open position, an actuating member movably carried by said head and having means operatively related to said die opening and closing member for moving said opening and closing member to closed position by motion of said actuating member in one direction and by further motion in the same direction to locking position, and for releasing said opening and closing member to permit opening of said die by motion of said actuating member in the opposite direction, a die holder with respect to which said head has a limited axial motion, operative connections between said holder and actuating member causing the motion of said holder to press said head onto the work, causing relative axial motion between said head and

holder, to move said actuating member from locking to holding position, and means actuatable on threading of the work to a predetermined extent to move said member from holding position in releasing direction.

3. A die comprising a head, chasers supported by said head for motion between die open and die closed positions, a member movably carried by said head and having operative engagement with said chasers for closing or opening said die by motion of said member, means biasing said member to die open position, an actuating member rockably carried by said head and having means operatively related to said die opening and closing member for moving said opening and closing member to closed position by rocking motion of said actuating member in one direction and by further motion in the same direction to locking position, and for releasing said opening and closing member to permit opening of said die by rocking of said actuating member in the opposite direction, a die holder with respect to which said head has a limited axial motion, operative connections between said holder and actuating member causing the motion of said holder to press said head onto the work, causing relative axial motion between said head and holder, to rock said actuating member from locking to holding position, and means actuated by relative axial motion between said head and holder thereafter, as said head threads onto the work while said holder is stopped, to rock said member from holding position in releasing direction.

4. A die comprising a head, chasers carried by said head, a member movable on said head and operatively connected to said chasers for opening and closing said die, means tending to open said die, a holder supporting said head for limited relative axial motion, an actuating member for said opening and closing member movably carried by said head, said actuating member being movable on said head between die open, die closed, and die closed locking positions, and operatively connected to said opening and closing member, causing motion of said actuating member from die open to die closed position to move said opening and closing member to die closed position, and means carried by said holder effective by relative motion of said holder and head as said head is pressed onto the work by pressure exerted on said holder to move said actuating member from die closed locking position to die closed position, said die including means for moving said actuating member from die closed position sufficiently to permit said tending means to open the die when the work has been threaded to the desired extent.

5. A die comprising a head, a holder supporting said head for limited relative axial motion, chasers carried by said head and movable between die open and die closed positions, means tending to open said die, means for closing and releasing said die comprising a member rockably carried by said head and movable axially relative to said holder between limits, means biasing said member to an axial position spaced a predetermined amount from its rearward limit, a stop carried by said holder in position to limit the forward motion of said member relative to said holder only when said member is in locking angular position, means actuatable by forward motion of said member beyond said stopped position to turn said member from die closed to die open position, and means actuated by rearward motion of said member from its biased position to

turn said member from die locked angular position to die closed angular position in which die closed angular position forward motion of said member to die open position is permitted.

6. A die comprising a head, a holder supporting said head for limited relative axial motion, chasers carried by said head and movable between die open and die closed positions, means tending to open said die, means for closing and releasing said die comprising a member rockably carried by said head and movable axially relative to said holder between limits, means biasing said member to an axial position spaced a predetermined amount from its rearward limit, a sleeve carried by said holder parallel to its axis, said sleeve having a slot in one side thereof, said member having a portion projecting into said slot only when said member is in locking angular position, the forward wall of said slot then limiting the forward axial motion of said member, a rod slideable in said sleeve, means limiting the extent of sliding motion of said rod, said rod having a beveled face, said member having a beveled face for cooperation with the beveled face of said rod to rock said member into die released position, means yieldingly holding said rod at its forward limit of motion with its beveled face out of reach of said member beveled face when said member is in locked angular position but in position to cooperate with said member face either by retraction of said rod or by forward motion of said member beyond its lock limited position to cause rocking of said member from die closed to die open position, and means effective to turn said member from locked angular position to die closed position when said member is moved rearwardly from its biased axial position.

7. A die comprising a head, a holder for said head and relative to which said head may have limited axial motion, means tending to hold said head in one axial position between its limits, die closing and locking mechanism carried by said head, and operative connections between said mechanism and said holder causing axial motion of said head relative to said holder in one direction from said position to change said mechanism from locking to closed condition, and operative connections between said mechanism and holder causing the axial motion between said mechanism and head in the opposite direction from said position, when said mechanism is in die closed condition, to change said mechanism to die open condition.

8. A die comprising a head, a holder for said head and relative to which said head may have limited axial motion, means tending to hold said head spaced a predetermined amount from its rear limit of motion, means tending to return said head to said spaced position when displaced forwardly therefrom, die opening, closing and locking mechanism carried by said head, and operative connections between said mechanism and holder causing rearward motion of said head from said spaced position relative to said holder, as by threading of the die onto the work while said holder is stationary, to cause said mechanism when in die closed condition to be changed to die open condition.

9. A die comprising a head, a holder for said head and relative to which said head may have limited axial motion, means tending to hold said head spaced a predetermined amount from its rear limit of motion, means tending to return said head to said spaced position when displaced forwardly therefrom, die opening, closing and locking mechanism carried by said head, operative connections between said mechanism and holder causing rearward motion of said head from said spaced position, as by pressure exerted on said holder to start the die onto work, to condition said mechanism from die locked to die closed condition, operative connections between said mechanism and holder causing the forward motion of said head from said spaced position relative to said holder as by threading of the die onto the work while said holder is stationary, to cause said mechanism when in die closed condition to be changed to die open condition, and means for actuating said last-named connections to change said mechanism from die closed to die open position irrespective of any motion of said head relative to said holder.

10. A die comprising a head, a holder for said head and relative to which said head may have limited axial motion, means tending to hold said head spaced a predetermined amount from its rear limit of motion, means tending to return said head to said spaced position when displaced forwardly therefrom, die opening, closing and locking mechanism carried by said head, operative connections between said mechanism and holder causing rearward motion of said head from said spaced position, as by pressure exerted on said holder to start the die onto work, to condition said mechanism from die locked to die closed condition, and operative connections between said mechanism and holder causing the forward motion of said head from said spaced position relative to said holder as by threading of the die onto the work while said holder is stationary, to cause said mechanism when in die closed condition to be changed to die open condition, and other means effective to change said mechanism from die closed to open condition irrespective of head and relative to which said head may have any motion of said head relative to said holder.

11. A die comprising a head, a holder for said head and relative to which said head may have limited axial motion, means tending to hold said head spaced a predetermined amount from its rear limit of motion, means tending to return said head to said spaced position when displaced forwardly therefrom, die opening, closing and locking mechanism carried by said head, and operative connections between said mechanism and holder causing rearward motion of said head from said spaced position, as by pressure exerted on said holder to start the die onto work, to condition said mechanism from die locked to die closed condition, and operative connections between said mechanism and holder causing the forward motion of said head from said spaced position relative to said holder, as by threading of the die onto the work while said holder is stationary, to cause said mechanism when in die closed condition to be changed to die open condition, said holder having means cooperating with said mechanism when said mechanism is in die locked condition to prevent forward motion of said head relative to said holder from said spaced position sufficient to change said mechanism to die open condition.

12. A die comprising a head, a holder for said

head and relative to which said head may have limited axial motion, said head having a shank portion and said holder having a sleeve in which said shank portion is axially movable, a rod extending through said shank portion and having a head at its forward end for engagement of its rear face on said die head, and a reduced diameter rear end portion defining a shoulder, an element carried by said shank and through which said reduced diameter portion extends, said die head having a limited axial motion relative to said rod, spring means reacting between said element and said rod tending to hold said die head retracted with respect to said holder to the forward limit of axial motion of said die head relative to said rod, yielding means reacting between said die head and holder tending to hold said die head at said forward limit, die opening, closing and locking mechanism carried by said die head, and operative connections between said mechanism and said holder causing relative motion of said die head rearwardly from said forward limit of axial motion of said die head relative to said rod to condition said mechanism to die closed condition, and forward motion of said die head against the pressure of said spring means to change said mechanism to die open condition, said holder and mechanism having means cooperating when said mechanism is in die locked condition to prevent forward motion of said die head relative to said holder sufficient to change said mechanism to die open condition.

13. A die comprising a head, a holder for said head with respect to which said head has a limited axial motion, chasers carried by said head, a member movably carried by said head and in operative engagement with said chasers to close said chasers on motion of said member to a definite position and normally biased away from said position to open said chasers, a locking member movably mounted on said head and having three positions in each of two of which it engages said movable member and holds said movable member in chaser closed position, and in the third position it permits said movable member to move to said chaser open position, means engageable with said locking member when in one of its said two positions and actuatable to move said locking member to chaser open position when the die has threaded work to a predetermined extent, means for preventing operation of said engageable means to move said locking member to die open position from the other of said two positions, and elements on said holder and locking member cooperatively engaging, on motion of said head relative to said holder through pressure exerted on said head when said holder first presents said head to work to be threaded, to move said locking means from the other of said two positions to said one of said two positions.

14. A die comprising a head, a holder for said head with respect to which said head has a limited axial motion, chasers carried by said head and movable between open and closed positions, a member mounted on said head for axial motion and having parts operatively engaging said chasers to close said chasers on forward motion of said member from a retracted position in which said member holds said chasers open, spring means tending to hold said member in retracted chaser open position, and a locking member rockably carried by said head about an axis lengthwise of said head and having three angular posi-

tions, elements on said locking and axially movable members cooperating when said locking member is in either of two of said angular positions to hold said axial member in forward closed chaser position but permitting said axially movable member to assume chaser open position when said locking member is in the third angular position, cam parts on said locking member and holder cooperating on forward motion of said locking member with said head relative to said holder from an intermediate position to rock said locking member from one of said two positions to said third position to permit opening of said chasers, parts of said locking member and holder when said locking member is in the other of said two angular positions cooperating to prevent such forward motion of said head with respect to said holder, said locking member and holder having cam parts cooperating when said locking member is in said other angular position to rock said locking member from said intermediate position to said third position to permit opening of said chasers, parts of said locking member and holder when said locking member is in the other of said two angular positions cooperating to prevent such forward motion of said head with respect to said holder, said locking member and holder having cam parts cooperating when said locking member is in said other angular position by motion of said locking member rearwardly relative to said holder from said intermediate axial position, as when said head is pushed against the work by said holder, to rock said locking member from said other angular position to said one angular position, said first-mentioned holder cam part being mounted on said holder for motion toward said cooperating member part and provided with a portion for engagement with an actuating element by which said movable cam part may be moved to cooperate with its mating member part and cause said locking member to release said chasers to open.
